RATCHET RELAYS

Seymour Kessler, Wilmette, Ill., assignor to Zenith Radio Corporation, Chicago, Ill., a corporation of Delaware Filed Feb. 26, 1962, Ser. No. 175,533 3 Claims. (Cl. 74—142)

This invention is directed generally to ratchet relays, and more particularly, to a high sensitivity ratchet relay suitable for use in transistorized circuits.

Ratchet type relays, of course, are well known in the art and many designs have been evolved for different applications. In most, the ratchet part of the relay has assumed the rather classical form of a toothed ratchet wheel, a reciprocating pawl which engages the teeth of the wheel, and an additional pawl for preventing backward motion. The reciprocating pawl usually includes a resilient ratchet device for engaging the teeth and some type of reciprocating lever. In operation, the ratchet device is moved in one direction, corresponding to the backward motion of the toothed wheel which the pawl prevents, and then in the other direction where the ratchet device engages a tooth of the wheel to rotate the wheel one step in a forward direction. This classical form of a ratchet is fully illustrated in almost any postwar issue of Webster's Collegiate Dictionary.

It is apparent that the ratchet must be flexible since during its backward motion it must "ride up" over a ratchet tooth. In the past, this has usually been achieved by means of a flexible leaf spring biased against a pivoted member. With the advent of transistorized actuating circuits, which have relatively low power output capacity compared to vacuum tube circuits, the classical ratchet device has been found to require an excessive amount of energy to operate it; i.e., an amount of energy above the rated capacity of most transistors in general use today.

It is, therefore, a primary objective of this invention to provide an improved ratchet relay.

It is a specific object of this invention to provide a ratchet relay having a high sensitivity.

It is a further object of this invention to provide a ratchet relay easily operated by transistorized actuating sources.

It is still another object of this invention to provide a high sensitivity ratchet relay of simple and inexpensive construction.

In accordance with the invention, there is provided a high sensitivity ratchet relay comprising a supporting frame having a shaft journaled in it. A ratchet wheel is mounted for rotation with the shaft and in addition, a ratchet bracket is pivoted on the shaft and has two legs on opposite sides of the ratchet wheel, each of the legs having a guide channel of predetermined width extending radially outwardly from the shaft. A ratchet spring is retained by the bracket, the spring having a main portion of a thickness corresponding to the predetermined width of the guide channels extending through the guide channels in a direction substantially parallel to the shaft, captivated against relative movement perpendicular to the radial direction by the guide channels but free to move within the channels in the radial direction, and biased into engagement with the ratchet wheel. Means are provided for rotating the ratchet bracket and the ratchet spring to advance the ratchet wheel and rotate the shaft.

The features of the present invention which are believed to be novel are set forth with particularity in the appended claims. The invention, together with further objects and advantages thereof, may best be understood by reference to the following description taken in connection with the accompanying drawing, in the several

2

figures of which like reference numerals identify like elements, and in which:

FIGURE 1 is an elevational front view of a ratchet relay embodying the invention;

5 FIGURE 2 is an elevational rear view partially in section and partially cut away of the relay of FIGURE 1;

FIGURE 3 is a partial sectional view taken along line 3—3 of FIGURE 1; and

10 FIGURE 4 is a sectional view, partially cut away, taken along line 4—4 of FIGURE 3 but showing a portion of the mechanism in a different operating condition.

Referring now to FIGURES 1 and 2, an actuating coil 10 is mounted on a supporting frame 11. More specifically, the coil is supported by an iron core consisting of pole pieces 12 and 13 as best shown in FIGURE 2. Each pole piece is constructed of two sandwiched iron plates, and the core is fastened by a screw 14 to a tab 11a bent out from frame 11. An armature 15 of rectangular outer shape and composed of two sandwiched iron plates having a central rectangular aperture circumscribes the exterior of coil 10. It is resiliently pivoted on the bottom portion of pole piece 12 (not shown) by a leaf spring 16. Energization of coil 10 produces a flux path starting through pole pieces 12 and 13 extending through the bottom portion of armature 15 up through the legs of the armature and thence across the air gap between armature 15 and pole piece 13 above coil 10. Armature 15 is attracted toward pole piece 13 pivoting in a counterclockwise direction as shown in FIGURE 2 to actuate the relay in a manner to be described below.

35 The final result of the actuation of armature 15 is to rotate a conductive wiper arm 17, as shown in FIGURE 1, in a stepped type of motion into successive contact with a conductive contact surface 18. Conductive surface 18 may be formed of silver paint printed on an insulating board 19 which is fastened to frame 11 by fasteners 20. The stepped motion of wiper arm 17 causes it to engage contact surface 18 every other rotational step, alternately making and breaking electrical contact.

40 A typical example of the use of such a switching device is in a remotely controlled television receiver where it is desired to remotely mute and unmute the audio of a television receiver. In such a case, switch 17, 18 may be inserted in series with a lead to the loudspeaker of the television receiver.

45 The above portion of the relay which has been described is entirely standard in the art and may be modified as desired.

50 The invention is specifically directed to a novel mechanism for coupling armature 15 to wiper arm 17, which mechanism includes a shaft 22 affixed to wiper arm 17 by a screw 23. Referring now to FIGURES 3 and 4, shaft 22 is journaled in frame 11 by a bearing bracket 24 which is affixed to the frame by fasteners 20 and is also journaled in insulating board 19. A ratchet bracket 25 is pivoted on shaft 22 and has a bight portion 26 and two legs 27 and 28 through which shaft 22 extends. A ratchet wheel 30 is fixed to, and thus mounted for rotation with, shaft 22 between legs 27 and 28. Legs 27, 28 are provided with respective guide channels or slots 33, 34 which extend in a direction radially away from shaft 22 as best shown in FIGURE 4.

55 A pawl or leaf spring 29, as best shown in FIGURE 2, is mounted on a tab 31 extending from frame 11 and engages the teeth of wheel 30 to prevent backward motion in the counterclockwise direction.

60 The ratchet mechanism of the relay includes a wire ratchet spring 35 which is retained in slots 33 and 34 in bracket 29. The ratchet spring includes a resilient multiple loop portion 36 and a main or straight portion 37

which extends through and is retained in guide slots 33 and 34. Portion 37, as retained in the slots, extends in a direction substantially parallel to shaft 22 as best shown in FIGURE 4. Moreover, guide slots 33 and 34 secure portion 37 against relative movement with respect to bracket 25 in a direction perpendicular to shaft 22. Multiple loop portion 36 is captivated on bracket 25 by a bent over end portion 39 which curves around the lower portion of slot 34. Straight portion 37 is captivated by a second bent end portion 40 which curves around the top of slot 33. End portions 39 and 40 are not anchored but serve to retain spring 35 in place by virtue of the resilience of loop portion 36 which biases the two end sections outwardly. Multiple loop portion 36 of spring 35 also serves to bias straight portion 37 into engagement with ratchet wheel 30. The fulcruming of loop portion 36 at the lower end of slot 34 allows lateral displacement of straight portion 37 against the biasing force of loop 36 to ride over the teeth of wheel 30 during the return stroke.

The amount of force needed to laterally displace portion 37 is considerably reduced because of two major factors. First, both ends of portion 37 are freely movable due to the fulcruming of loop portion 36 at the lower end of slot 34. Secondly, the retention of straight portion 37 by guide slots 33 and 34 effectively prevents relative perpendicular movement thereby allowing ratchet spring 35 to have more flexibility in the radial direction.

Ratchet bracket 25 and its associated ratchet spring 35 are coupled to armature 15 in a manner which achieves 30 the reciprocating motion necessary in ratchet relays of this type. This mechanism includes a drive rod 41 (FIGURES 2 and 4) journaled in a bearing 42 which is inserted in frame 11 and pole piece 13. One end of the rod is coupled to ratchet bracket 25 by a pin 43, and the 35 other end is unilaterally coupled to armature 15 by means of a drive rod adjusting screw 44 which is mounted on an extension 45 of armature 15. Ratchet bracket 25 is biased in a clockwise direction by a return spring 47 having one end coupled to ratchet bracket 25 and the 40 other to a bent out tab 48 of frame 11. Clockwise rotation of bracket 35 in response to the bias of spring 47 is limited by a collar 49 on drive rod 41 which abuts against bearing 42.

A conductive connection is made to wiper arm 17 as 45 shown in FIGURE 3 by means of a ground spring 50. The spring is mounted on bearing bracket 24 to bear against a necked down portion of shaft 22. Spring 50 grounds shaft 22 to frame 11 which in turn is grounded to the chassis upon which it is usually placed. 50

Operation

Repetitive energization of coil 19 successively steps wiper arm 17 into and out of contact with contact surface 18. As shown in FIGURE 1, wiper arm 17 rotates in a counterclockwise direction in response to rotation of shaft 22 by ratchet wheel 30. Ratchet bracket 25 is shown in its reference position in FIGURES 2 and 3 with coil 19 de-energized and armature 15 in its rest position. The bias of spring 47 on ratchet bracket 25 also serves 55 to hold armature 15 in its rest position by means of drive rod 41 engaging adjusting screw 44. Upon energization of coil 19, armature 15 is pivoted toward pole piece 13, thus pushing drive rod 41 to the left (as seen in FIGURE 4) and rotating ratchet bracket 25 in a counterclockwise 60 direction. During this rotation, herein termed the return stroke, straight portion 37 of ratchet spring 35 is cammed downwardly by the action of a ratchet tooth to the position shown by the dashed lines in FIGURE 3. When ratchet bracket 25 reaches its extreme counterclockwise 65 position, as shown in FIGURE 4, straight portion 37 of the ratchet spring drops into engagement with a preceding tooth. During this motion, backward movement of ratchet wheel 30 is prevented by pawl 29.

Upon de-energization of coil 19 return spring 47 re-

75 stores bracket 25 to its rest position to cause ratchet spring 35 to advance ratchet wheel 30, shaft 22, and wiper arm 17 one step.

It is apparent that the major work accomplished by the relay is in rotating ratchet bracket 25 from its rest position to an actuating position. To accomplish this, it must overcome the bias of return spring 47 thereby storing energy in it and also overcome the upward bias of straight portion 37 of the ratchet spring. Since the moving of ratchet spring 35 is all wasted energy, the minimization of this energy loss will produce a highly sensitive relay.

The design of ratchet spring 35 as disclosed in the present application greatly reduces energy loss as compared to prior art ratchet relays. Thus, an improved ratchet relay is disclosed having a high sensitivity making its utilization with transistorized actuating device practical. In addition, a relay of simple and inexpensive construction has been provided.

While a particular embodiment of the invention has 20 been shown and described, it will be obvious to those skilled in the art that changes and modifications may be made without departing from the invention in its broader aspects, and, therefore, the aim in the appended claims is to cover all such changes and modifications as fall 25 within the true spirit and scope of the invention.

I claim:

1. A high sensitivity ratchet relay comprising:
a supporting frame;
a shaft journaled in said frame;
a ratchet wheel mounted for rotation with said shaft;
a ratchet bracket pivoted on said shaft and having two legs on opposite sides of said ratchet wheel, each of said legs having a guide channel of predetermined width extending radially outwardly from said shaft;
a ratchet spring retained by said bracket, such spring having a main portion of a thickness corresponding to said predetermined width of said guide channels extending through said guide channels in a direction substantially parallel to said shaft, said main portion being captivated against relative movement perpendicular to said radial direction by said guide channels but free to move within said channels in said radial direction, and said main portion being biased into engagement with said ratchet wheel;
and means for rotating said ratchet bracket and said ratchet spring to advance said ratchet wheel and rotate said shaft.

2. A high sensitivity ratchet relay comprising:

a supporting frame;
a shaft journaled in said frame;
a ratchet wheel mounted for rotation with said shaft;
a ratchet bracket pivoted on said shaft and having a bight portion and two legs through which the shaft extends, each of said legs having a guide slot of predetermined width extending radially outwardly from said shaft, said ratchet wheel being fixed to said shaft between said legs;
a wire ratchet spring having a multiple loop portion and a straight portion of a thickness corresponding to said predetermined width of said guide slots coupled to one end of said multiple loop portion and extending through and retained in said slots in said shaft, said straight portion being captivated against relative movement perpendicular to said radial direction by said guide slots but free to move within said slots in said radial direction, such straight portion being biased into engagement with said ratchet wheel by said multiple loop portion, the other end of said multiple loop portion being fulcrumed on said bracket at a point more remote from said wheel than said straight portion;
and means for rotating said ratchet bracket and said ratchet spring to advance said ratchet wheel and rotate said shaft.

3. A high sensitivity ratchet relay comprising:
 a supporting frame;
 a shaft journaled in said frame;
 a ratchet wheel mounted for rotation with said shaft;
 a ratchet bracket pivoted on said shaft and having a 5
 bight portion and two legs through which the shaft
 extends, each of said legs having a guide slot of pre-
 determined width extending in a radial direction
 relative to said shaft, said ratchet wheel being fixed
 to said shaft between said legs;
 a ratchet assembly including a resilient wire loop por-
 tion and a straight portion of a thickness correspond-
 ing to said predetermined width of said guide slots
 having two ends extending through and retained in
 said slots in a direction substantially parallel to said 15
 shaft, such straight portion being biased into engage-
 ment with said ratchet wheel by said resilient wire
 loop portion;
 means including an actuating coil and an armature
 coupled to said ratchet bracket for displacing said 20
 ratchet bracket from a rest position;

6
 said resilient wire loop portion being fulcrumed on
 said bracket at a point displaced from said straight
 portion to allow free lateral movement of said
 straight portion at both of said ends against the bias-
 ing force of said loop portion during displacement
 of said ratchet bracket from its rest position while
 captivating said straight portion in said slots against
 relative motion perpendicular to said radial direc-
 tion;
 and return means for restoring said bracket to said rest
 position to cause said ratchet assembly to advance
 said ratchet wheel and rotate said shaft.
